UNITED STATES PATENT OFFICE.

ERASTUS E. WINKLEY, OF LYNN, MASSACHUSETTS, ASSIGNOR TO UNITED SHOE MACHINERY COMPANY, OF PATERSON, NEW JERSEY, A CORPORATION OF NEW JERSEY.

AUTOMATIC SOLE-LEVELING MACHINE.

1,054,263.

Specification of Letters Patent. Patented Feb. 25, 1913.

Application filed October 3, 1910. Serial No. 585,030.

To all whom it may concern:

Be it known that I, ERASSTUS E. WINKLEY, citizen of the United States, residing at Lynn, in the county of Essex and State of 5 Massachusetts, have invented certain new and useful Improvements in Automatic Sole-Leveling Machines; and I do hereby declare the following to be a full, clear, and exact description of the invention, such as will enable others skilled in the art to which it ap- 10 pertains to make and use the same.

The present invention relates to certain new and useful improvements in automatic sole leveling machines, and more particu- 15 larly to the jack adjusting mechanism em- ployed upon such machines. Sole leveling machines of this general type are provided with mechanism for oscillating the shoe sup- 20 porting jacks automatically beneath the lev- eling rolls, manually operated means being provided for adjusting this mechanism in order to vary the oscillations of the jack as desired. In the present type of machine, however, the manually operated control is 25 located in the lower part of the machine and is not conveniently accessible to the hand of the operator when it is found necessary to use it.

The object of the present invention is to 30 provide a jack adjusting mechanism to which the operator may have convenient access and which is simple and efficient in its operation.

With the above object in view, the invention 35 consists of the features of construction which will be described in the following specification and defined in the appended claims.

In the accompanying drawings illustrating the preferred form of the invention Fig- 40 ure 1 represents a side elevation of an auto- matic sole leveling machine with the im- proved jack adjusting mechanism applied thereto. Fig. 2 is a detail with a portion in section, showing a front view of the ad- 45 justing mechanism.

Referring to the drawings in which like characters of reference indicate like parts, 1 represents the frame of the machine, 2 the leveling rolls, 3 the roll carriers and 4 the 50 roll carrier beds pivotally mounted at 5 upon the frame of the machine, so as to be free to tip longitudinally. The rolls 2 are given rapid reciprocating or vibrating movements in the roll carriers 3 through suitable 55 connections from the driving shaft 7 mount-

ed in bearings in the upper rear portion of the machine frame and constantly rotated by a driving pulley 9 secured to the shaft. The carrier beds are acted upon by springs 10 to swing the beds on their pivot 5 and 60 press the leveling rolls against the soles of the shoes on the shoe supporting jacks. The shoe supporting jacks are represented at 11 and are arranged to oscillate beneath the leveling rolls, as will be hereinafter de- 65 scribed. Each of the jacks 11 is loosely piv- oted by means of sleeves 17 upon a shaft 18 journaled in the front portion of the ma- chine frame. Situated between the sleeves 17 on the shaft 18, and loosely mounted 70 thereon, is a sleeve 19, to which is secured a downwardly extending arm 20. Adjust- ably mounted in an arc-shaped slot in the arm 20 is a slide block 21, to which is pivot- ally connected a link 22, the other end of 75 which is provided with a roll engaging a path cam 23, secured to a wheel or disk 15, and which is pivotally connected to the upper end of an arm or lever 24, pivoted at 25 in the rear lower portion of the machine frame. 80 By this construction, as the shaft 18 is ro- tated, the sleeve 19 will be oscillated, and if either jack is connected to the sleeve, the jack will be oscillated beneath its correspond- 85 ing leveling roll. When the jacks are dis- connected from the sleeve 19, they fall back of their own weight and rest against stops 26 carried by brackets extending forwardly 90 from the machine frame. For connecting either jack to the sleeve 19, so as to be oscil- 95 lated thereby beneath its corresponding lev- eling roll, the sleeve 19 is provided with ra- dially extending arms 27, the outer ends of which are connected by a hollow rod 28, in which are seated spring pressed pins 29, 95 only one of which is shown in Fig. 2, the pins 29 being adapted to enter holes 30 in the jack frames when the jacks are moved into a position in which the holes register the pins. Each jack frame is provided with 100 a segmental guard plate 31, which prevents the pins 29 from being forced outwardly, except when the holes 30 register with the pins.

The mechanism above described, and all 105 other mechanisms shown in the drawings, and not hereinafter described, are the same in all essential particulars as those dis- closed in the patent to Winkley, No. 677,315, June 25, 1901, to which reference may be 110

had for a full description of the construction and mode of operation.

It is desirable to vary the travel of the shoe supporting jack when operating upon 5 different classes of work, and the present invention comprises an improved mechanism for accomplishing this result expeditiously. The block 21 is slidably mounted in the arc shaped slot 32, and is retained in 10 any adjusted position by a link 33 pivotally connected thereto, the movement of the link 33 being controlled by a lever 34 pivotally connected to the upper end of the link. The lever 34 is loosely sleeved upon the shaft 18 15 and has a laterally projecting front portion 35 carrying an operating handle 36 and a spring pressed latch 37 of any convenient form. The latch 37 is adapted to engage with a toothed segment 38, which is rigidly 20 mounted upon the sleeve 19 to oscillate therewith. The block 21 may be adjusted to any position in the slot 32 by moving the handle 35, the mechanism being retained in this adjusted position by the spring pressed 25 latch 37 engaging with the toothed segment 38.

Having thus described the invention, what is claimed as new is:—

1. A sole leveling machine having, in 20 combination, a leveling roll, a shoe supporting jack, a shaft about which the jack is oscillated, a depending slotted arm for oscillating the jack, a slide block supported in the arm, an adjusting lever fulcrumed upon 25 the shaft and having a handle conveniently accessible to the operator, means for locking the lever in adjusted position, and connections between the lever and slide block

to adjust the slide block in the arm and vary the oscillations of the jack.

2. A sole leveling machine, having, in 40 combination, leveling rolls, a plurality of shoe supporting jacks, a shaft about which the jacks oscillate, actuating mechanism for the jacks, comprising a sleeve mounted upon the shaft between the jacks, a slotted arm depending from the sleeve, a slide block adjustably held in the slotted arm, means for actuating the block to oscillate the sleeve, means for operatively connecting either jack 45 to the sleeve, and mechanism mounted upon the shaft independently of the jacks and adapted to adjust the slide block in the slotted arm, substantially as described.

3. A sole leveling machine, having, in 50 combination, leveling rolls, a plurality of shoe supporting jacks, a shaft about which the jacks oscillate, actuating mechanism for the jacks, comprising a sleeve mounted upon the shaft between the jacks, a slotted arm 55 depending from the sleeve, a slide block adjustably held in the slotted arm, means for actuating the block to oscillate the sleeve, means for operatively connecting either jack to the sleeve, and adjusting mechanism for 60 the slide block comprising a lever loosely sleeved upon the shaft, connections between the lever and slide block, and a toothed segment mounted upon the sleeve and adapted to coöperate with the lever to retain the 65 slide block in any adjusted position, substantially as described.

ERASTUS E. WINKLEY.
